UNITED STATES PATENT OFFICE

93,983

DESIGN FOR AN AIRPLANE

James H. Kindelberger, Los Angeles, Calif., assignor to General Aviation Manufacturing Corporation, Dundalk, Md., a corporation of Delaware

Application October 9, 1934, Serial No. 53,526

Term of patent 14 years

To all whom it may concern:

Be it known that I, JAMES H. KINDELBERGER, a citizen of the United States of America, residing at Los Angeles, in the county of Los Angeles, and State of California, have invented a new, original, and ornamental Design for an Airplane, of which the following is a specification, reference being had to the accompanying drawings forming a part thereof.

In the drawings:

Figure 1 is a top plan view of an airplane showing my new design;

Figure 2 is a front elevation thereof;

Figure 3 is a side elevation thereof;

Figure 4 is an isometric perspective thereof.

I claim:

The ornamental design for an airplane substantially as shown.

J. H. KINDELBERGER.
